GUARD FOR SPRAY GUNS

Lawrence W. Cornelison, San Francisco, Calif.

Application February 10, 1937, Serial No. 124,974

9 Claims. (Cl. 91—65)

This invention relates to guards for spray guns.

It is the primary object of the invention to provide a guard for spray guns whereby the spraying of an article may be limited to a certain width and whereby the spreading of the spray beyond the area defined by the guard is obviated.

Particularly it is the object of the invention to provide a guard for portable spray guns, which guard is adapted to engage the longitudinal edges of a strip like article, such as a molding; the guard being urged into slidably gripping engagement with the edges of the molding so that it may be advanced thereon with the spray gun as the molding is sprayed thus preventing the spreading of the spray beyond the edges of the molding, and protecting the body on which the molding is mounted.

Other objects and advantages are to provide a guard for spray guns that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawing wherein

Fig. 1 is a side view of the spray guard in operative position; and

Fig. 2 is a front view of the spray guard on the molding.

Spray guns are in general use at present for the purpose of applying paint or coating to various articles. It is difficult to prevent the spreading of the spray beyond the boundaries of the article and to prevent the soiling of bodies adjacent to the article painted. This difficulty presents itself especially in the painting of ornamental strips, such as moldings, mounted on the side or wall of a body. In the automotive industry the molding on the body of the automobile is frequently of a different color than the body itself. In painting the molding it is necessary to advance the spray gun alongside the molding or ornamental strip. Usually the body of the automobile adjacent the molding is covered with canvas, or paper, or the like in order to protect the body itself from the spray.

55 A spray gun provided with a guard, constructed

in accordance with my invention, limits the impingement of the spray to the width of the ornamental strip or molding, without necessitating the covering of the automobile body adjacent the molding. In fact, my guard may be used for spraying any article in such manner as to confine the impingement of the spray on the article to a definite area.

In carrying out my invention I make use of a portable spray nozzle 6, connected by a flexible conduit 7 to the usual mechanism supplying the fluid or paint under pressure.

On the nozzle 6 is placed a guard support or nozzle holder 8, having an elongated slot 9 therein, thru which the nozzle 6 extends. A washer 11 is disposed on the nozzle 6 on each side of the slot 9. The washers 11 are larger than the width of the slot 9 and are held against the respective sides of the support 8, by nuts 12 fastened on the threaded portion 13 of said nozzle 6. In this manner the nozzle 6 is securely held in the support 8 in various desired, angular positions.

On each end of the support 8 is pivotally mounted a shield 14 by means of hinges 15, so that the shields 14 are in opposed relation and may be swung toward and away from each other. The free edges 16 of the shields 14 are preferably parallel with the pivot of the hinges 15, and abut each other opposite the nozzle 6.

On the pivot pin of each hinge 15 is disposed a coil spring 17, the opposite ends of which bear against the respective hinge sections so as to urge the shields 14 toward each other. On the support 8 is mounted or formed a handle 19 to facilitate the carrying and moving of the guard. In this illustration the guard is shown in a substantially cylindrical form, however, the guard may be constructed in other suitable forms.

In operation the edges 16 of the shields 14 are placed on the opposite longitudinal edges 21 of a molding 22, thereby defining the width of the strip on which the spray issued from the nozzle 6, impinges. The wall 23 on which the ornamental strip or molding 22 is mounted is protected from the spray by the said shields 14. The tension of the springs 17 is such that the molding 22 is gripped between the shield edges 16 on the respective mold edges 21.

The guard is held by grasping the handle 19 and it is readily advanced on the molding 22 for painting the length of the ornamental strip. The wall or side 23 of the body is freely protected from the spray at all times. The nozzle 6 may be angularly adjusted in the slot 9 so as to direct the spray to certain portions of the strip in a desired

manner. The guard is of sufficient length to prevent the escapement of the spray thru the open ends thereof, however, if necessary, the nozzle may be boxed in entirely, thereby to define, in all directions, the area to be sprayed.

5 Having thus described this invention, what I claim and desire to secure by Letters Patent is:

1. In a device of the character described, a nozzle holder, means on the holder adapted to be slidably engaged with an article to confine the spray to a desired area of said article, and means to urge the said confining means to slidably grip the said article.
- 10 2. In a device of the character described, a portable nozzle holder, means on the holder adapted to be slidably engaged with an article to confine the spray to a desired area of said article, and means to urge the said confining means to slidably grip the said article.
- 15 3. In a device of the character described a portable nozzle holder, means on the holder adapted to engage the opposite edges of a strip of material to confine the spray issued from the nozzle on the area between said edges, and means to urge said confining means into slidable engagement with the edges of said strip so as to permit the said confining means to follow the contour of said edges as the device is moved alongside the strip.
- 20 4. In a device of the character described, a portable nozzle holder, shielding means on the holder to slidably engage the edges of an object to be sprayed, and resilient means to urge the said shielding means into slidable engagement with the said object so as to define the area to be sprayed.
- 25 5. In a device of the character described, a pair of opposed shields, means of connection between the shields arranged to allow the movement of a free edge of one shield toward and away from the corresponding free edge of the other shield; means to urge a shield toward the

other so as to slidably grip an article between the free edges of the shields; and sprayer means operatively related to said shields to direct a spray between the shields upon the article between the said gripping edges.

5

6. In a device for spraying a strip of material, a spray nozzle holder; guard means on the holder for slidably engaging opposite longitudinal edges of a strip of material to confine the impingement of the spray only to the width of the strip confined; and means to resiliently urge said guard means against the respective strip edges to permit the sliding of the guard alongside said strip.

7. In a device for spraying a strip of material, a spray nozzle holder; guard means on the holder for slidably engaging opposite longitudinal edges of a strip of material to confine the impingement of the spray only to the width of the strip confined; means to resiliently urge said guard means against the respective strip edges to permit the 15 sliding of the guard alongside said strip; and a spray nozzle being adjustably held in the said holder and being connected to a fluid conduit.

8. In a mold spraying device, a spray nozzle holder, opposed shields pivotally mounted thereon to be swingable toward and away from each other, resilient means to urge the shields toward each other and into slidable engagement with the edges of the mold, thereby to limit the 20 impingement of the spray to the width of the 25 mold.

9. In a mold spraying device, a spray nozzle holder, opposed shields pivotally mounted thereon to be swingable toward and away from each other, resilient means to urge the shields toward each other and into slidable engagement with the edges of the mold, thereby to limit the 30 impingement of the spray to the width of the 35 mold; and a spray nozzle being adjustably held in the said holder and being connected to a fluid conduit. 40
